UNITED STATES PATENT OFFICE.

HERBERT W. EDMUNDSON AND WILLIAM T. MUNRO, OF RUGBY, ENGLAND,
ASSIGNORS TO GENERAL ELECTRIC COMPANY, A CORPORATION OF NEW
YORK.

VACUUM ELECTRIC DISCHARGE DEVICE.

Application filed March 10, 1919. Serial No. 281,649.

To all whom it may concern:

Be it known that we, HERBERT WATSON EDMUNDSON and WILLIAM TOM MUNRO, subjects of the King of Great Britain, residing at Rugby, in the county of Warwickshire, England, have invented certain new and useful Improvements in Vacuum Electric Discharge Devices, of which the following is a specification.

- 10 Our invention relates to vacuum electric discharge devices of the kind known as valves, rectifiers or the like such as are used in wireless telegraphy and for other purposes in which a heated cathode is employed.
- 15 The object of our invention is to provide an improved discharge device in which the destructive effects resulting from the heat produced in the anode by the bombardment of the electrons from the cathode are eliminated as far as possible.

According to our invention a shield preferably of metal is mounted within the device in such a position as to cut off the heat radiated from the anode during operation of 25 the device. This shield may be of different shape according to the construction of the discharge device, and is separated from the anode so that the vacuous space between it and the latter serves to prevent it from becoming heated to any considerable extent.

In applying the invention to a form of valve in which the cathode is located within a cylindrical anode, the whole being mounted on a glass stem within an evacuated bulb, 35 the stem carrying the leading-in conductors for the device, the shield may be in the form of a cylinder of thin sheet metal almost completely, or completely, surrounding the anode or interposed between the anode and stem 40 in any convenient way so as to prevent the stem through which the leading-in wires pass from being heated by direct radiation from the surface of the anode. As a result the heat radiated from the anode will be prevented from injuriously affecting the seal.

If allowed to act on the seal the heat radiated from the anode might cause electrolysis with the evolution of gas from the glass itself. This heat might also cause 45 cracks to form along the leading-in conductors thus allowing the surrounding gases to leak into the interior of the device and impair the vacuum. In de-

vices of the general class to which our invention relates, the allowable voltages which may be applied between the various leading-in conductors depends largely upon the temperature of the glass between the conductors. It is therefore of importance, where high voltages are to be used, that the seals should be maintained at as low a temperature as possible.

The accompanying drawings illustrate one form of our invention, Fig. 1 being an end elevation and Fig. 2 a side elevation partly broken away.

In the drawing, 1 represents an evacuated receptacle provided with the glass stem 2 into which the supporting wires and the conductors through which current is supplied 70 to the various parts are sealed. 3 is a filament adapted to operate as a hot cathode, and 4 is the anode which receives the bombardment of electrons given off by the cathode. Surrounding this anode we provide 75 a shield 5 which is held in place by a support 6 sealed into the stem 2. In the modification illustrated the shield is formed by doubling a sheet of thin metal and bending it into the form of a cylinder, the two portions of the 80 plate being spaced apart so that they form substantially two concentric cylinders concentric with the anode 4, which in this case is shown as a cylinder. The shield 5 may be secured to the supporting wire 6 in any convenient manner, for example, a tongue 7 may be stamped from the sheet in proximity to the bend and bent upwards. This tongue may be soldered or welded to the end of the supporting wire in any well known suitable 85 manner.

The shield also prevents conductive material due to the disintegration of the anode or cathode from being deposited on the stem and seals where it is usually largely deposited and where it may act as a conductive bridge between the leading-in wires and impairs the efficiency of the device.

While we have illustrated and described only one form of our invention, it will be apparent to those skilled in the art that many variations may be made in the form of the shield as well as in the manner in which it is placed and supported in the device without departing from the scope of our invention as set forth in the appended claims.

What we claim as new and desire to secure by Letters Patent of the United States, is,—

1. The combination in an apparatus of the class described of an evacuated receptacle containing a cathode adapted to be heated to incandescence and an anode adapted to receive electrons from said cathode, leading-in conductors sealed into the walls of said receptacle for supplying current to said cathode and anode, and a shield interposed between said anode and the region where said leading-in conductors are sealed into the walls of the receptacle for intercepting heat radiated from the anode said shield being out of contact with the walls of the receptacle.

2. The combination in an apparatus of the class described of an evacuated receptacle containing a filamentary cathode adapted to be heated to incandescence and an anode adapted to be bombarded by electrons from said cathode, leading-in conductors sealed into the walls of said receptacle for supplying current to said cathode and anode, and a shield interposed between said cathode and anode and the region where said leading-in conductors are sealed into

the walls of the receptacle for preventing the overheating of that region of the walls 30 which surrounds the leading-in conductors said shield being out of contact with the walls of the receptacle.

3. The combination in an apparatus of the class described of an evacuated receptacle containing a cathode, an anode which is adapted to be bombarded by electrons from said cathode, leading-in conductors for supplying current to said cathode and anode, a stem for said receptacle through which said 40 leading-in conductors are sealed, and a shield interposed between said cathode and anode and said stem for preventing the overheating of the stem said shield being out of contact with the walls of the receptacle.

In witness whereof, we have hereunto respectively set our hands the 12th day of February, 1919, and the 8th day of March, 1919.

H. W. EDMUNDSON.

WILLIAM T. MUNRO.

Witness to the signature of the said Herbert Watson Edmundson:

JOHN HALFORD,
DOROTHY WHITE.
